CLAIM

I claim the ornamental design for a bank of combined gaming machines and displays, as shown and described.

DESCRIPTION

FIG. 1 is a perspective view of the bank of combined gaming machines and displays in accordance with the new design. FIG. 2 is a right side view of the bank of combined gaming machines and displays.

FIG. 3 is a left side view of the bank of combined gaming machines and displays.

FIG. 4 is a top view of the bank of combined gaming machines and displays.

FIG. 5 is a front view of the bank of combined gaming machines and displays; and,

FIG. 6 is a back view of the bank of combined gaming machines and displays.

The broken line showing portions of the bank of combined gaming machines and displays depicts environment and forms no part of the claim.

1 Claim, 6 Drawing Sheets
